UNITED STATES PATENT OFFICE.

THOMAS F. KELLY, OF CLINTON, IOWA, ASSIGNOR OF ONE-HALF TO JOSEPH A. KELLY,
OF CLINTON, IOWA.

BED-DAVENPORT.

1,381,843.

Specification of Letters Patent. Patented June 14, 1921.

Application filed October 15, 1920. Serial No. 417,114.

To all whom it may concern:

Be it known that I, THOMAS F. KELLY, a citizen of the United States, residing at Clinton, in the county of Clinton and State 5 of Iowa, have invented new and useful Improvements in Bed-Davports, of which the following is a specification.

The primary object of my invention is to provide an improved davenport-bed to the 10 end that the upholstered back of the davenport may be readily displaced in order that the folded bed portion of the same may become accessible. These improvements are particularly applicable to davenport-beds in 15 which the mattress and the supporting frame for the same are foldable into the back portion of the davenport and are normally concealed from view by the upholstered back thereof. In the patents to William J. Kelly 1,223,798 dated April 24, 20 1917 and 1,270,839 dated July 2, 1918 structures of this general type are shown, but it will be noted that in these patents the upholstered back of the davenport or sofa is 25 pivotally connected to a truss bar of the mattress supporting frame so that when the bed is in extended position the said back portion depends from the truss bar in such manner as to help support the bed.

According to my invention, however, the back portion of the davenport does not move with the sectional mattress support but moves independently thereof in order that the mattress may be readily accessible 30 when in folded position and as readily replaced within the davenport.

The invention is described in connection with the accompanying drawings, in which:

Figure 1 is a vertical sectional view of the 40 back in raised position, the cushion portion of the davenport being shown in elevation with parts broken away and the bed of the davenport-bed being shown in extended position.

Fig. 2 is a view similar to Fig. 1 showing the position assumed by the back when the bed is folded.

Fig. 3 is a front view of the davenport showing the back portion in raised position 50 and the bed in folded position.

The supporting frame of the davenport-bed is designated generally by the numeral 10 and includes end frame members 11 connected by the upholstered seat section 12.

55 The folding bed portion of the davenport

may be designated as a whole by the numeral 13 and is conventionally shown as consisting of a foldable mattress and a frame 15 consisting of a plurality of sections pivotally secured together, said sections having supporting legs 16, 17 pivotally secured thereto. As described in the patents above referred to, the bed part of the davenport is foldable into a space 18 in the rear of the said cushion 12. A truss bar 19 is connected to an opposite pair of sections of the mattress supporting frame in order to add rigidity to the same and as explained in Patent 1,223,798, above mentioned, this truss bar may have interposed between it and the woven wire fabric of the mattress spring a series of spiral springs for the purpose of providing an additional support for the mattress.

When the mattress and its supporting frame are in folded position in the rear portion of the davenport the truss bar 19 extends upwardly as shown in Fig. 3 and is secured in position by means of a spring pressed clip 20 consisting of a body portion 21 secured to the back 22 of the frame 10 and a spring-pressed locking element 23 pivoted to the body 21.

The frame 10 is provided with the usual arm rests 24 from which standards 25 extend upwardly, said standards being connected at their upper ends by means of the cross piece 26 and angle braces 14 secured to the standards and the cross piece. The back portion of the davenport consists of a substantially rectangular frame 27, slightly curved at its upper end as indicated at 28, which frame is covered with the usual upholstering 29. According to my invention the upholstered back is hinged near each end 90 to the cross piece 26 by means of angle plates 30 having one side fastened to said cross piece and to the outstanding side of the angle plate an arm 31 is pivotally connected by means of a pin 32. A metallic plate 33 is secured to the end members 27' of the rectangular frame 27 by means of screws 34 and the free end of the arm 31 is pivotally connected to said plate at an intermediate point by means of a pin 35.

A link 36 having a slot 37 therein is pivotally connected to one end of the plate 33 by means of a pin 38 and is slidably connected to the arm 31 by means of a pin 39 engaging in the slot 37. With this hinged construc- 100 105 110

tion, in order to gain access to the folded bed it is only necessary to raise the back of the davenport in which case the back will pivot about the pins 32 and the link 36 will move relatively to the pin 39 until said pin is located at one end of the slot 37 in which position the curved end of the upholstered back rests against the back of the frame 10 and its weight is so disposed that the same tends to remain in this position with stability so that there is no danger of the back accidentally closing. With the back in the raised position it is evident that to extend the bed, it is only necessary to manually release the catch 20 and pull on the truss rod 19 which will place the bed over the cushion 12 of the davenport but out of contact therewith, said cushion always remaining in fixed position. The back 29 may be lowered when the bed is in folded position or when the same is extended, in which case the arms 31 will pivot about the pins 32 and the back may pivot about the pin 35 so that the link 36 will move relatively to the pin 39 until the upholstered back reaches its correct position relatively to the cushion.

Having described my invention what I claim as new and desire to secure by Letters Patent, is:—

30 1. In a davenport-bed, a frame having end members and a fixed cushion, a movable back portion, standards rising above said

end members, a cross-piece connecting said standards, an angle plate secured to said cross-piece, a metallic plate fastened to said back portion, an arm pivotally connected at each end to said plates, a slotted link pivotally connected to said metallic plate and a pin secured to said arm engaging in the slot of said link.

2. In a davenport-bed having a frame adapted to receive the folded bed, and a movable back portion, a hinged connection between said back portion and frame consisting of an arm pivotally connected to said frame and back portion and a link pivotally connected to said back portion having a pin and slot connection with said arm.

3. In a davenport-bed having a supporting frame, a movable back portion, a rigid arm pivotally connected to the back portion and frame whereby the back portion may move to an inverted position with the normally upper part of the same in the rear of the frame, and means for limiting the pivotal movement of said back portion relatively to said arm.

In testimony whereof I have hereunto set my hand in presence of two subscribing witnesses.

THOMAS F. KELLY.
